UNITED STATES PATENT OFFICE.

ALBERT WILLSON, OF WINSLOW, ARIZONA.

BRAKE-DOG.

1,137,300.

Specification of Letters Patent. Patented Apr. 27, 1915.

Application filed January 22, 1913. Serial No. 743,573.

To all whom it may concern:

Be it known that I, ALBERT WILLSON, a citizen of the United States, residing at Winslow, in the county of Navajo and State 5 of Arizona, have invented new and useful Improvements in Brake-Dogs, of which the following is a specification.

My present invention relates to improvements in brake mechanism for railway cars, 10 vehicles, hoisters, derricks and other machinery, and it has primarily for its object the provision of a specially devised spring controlled ratchet dog or pawl, of such novel and peculiar construction as to be readily 15 shifted and retained in co-operative relation or in engagement with the ratchet wheel, or in such a position as to permit unobstructed rotation of the same.

A further object of the invention is to 20 provide a pair of specially arranged leaf or plate springs, so disposed in relation to the dog or pawl as to normally control the movement thereof, yet permit the desired adjustment should occasion demand.

With the above and various other objects 25 in view the invention consists essentially in the provision of a dog or pawl having a diamond shaped lug or projection provided upon one face thereof, the latter adapted 30 to fit between two oppositely disposed leaf or plate springs carried by or mounted within a suitable casing in such a manner as to control the movement of the dog, yet permit of its adjustment as desired.

Certain other features of construction together with the combination and arrangement of the several parts as will be hereinafter fully described and specifically pointed out in the appended claims must be 40 reasonably considered in determining the advantages and novel features of this invention.

In describing my invention in detail reference will be had to the accompanying 45 drawings wherein like characters denote like or corresponding parts throughout the several views, and in which:—

Figure 1 is a plan view illustrating the application of the invention. Fig. 2 is an 50 enlarged detail view of the dog and its operating mechanism, the casing being shown in section, and Fig. 3 is a section on line 3—3 of Fig. 2.

Referring now more particularly to the drawings wherein is illustrated the preferred form of my invention the numeral 1 designates the car or other platform, and 2 the vertically extending brake operating shaft, having the usual ratchet wheel 3 keyed or otherwise secured thereto. 55 60

A plate member 4 is secured to the platform 1, and is provided with a pair of vertically extending screw threaded bolts 5. A pawl or ratchet dog 6 is pivotally mounted through the medium of a third vertically 65 extending screw threaded bolt or pin 7, upon the said platform, in such a manner as to normally engage the teeth of the ratchet wheel 3. A diamond shaped lug or projection 8 is formed integral with and projects 70 upwardly from the top face of the pawl, through which the pin 7 extends, the purpose of this projection to be hereinafter fully described.

A suitable casing 9 having a pair of elongated apertures 10 through which the bolts 5 extend, is loosely mounted upon the plate member 4 and extends transversely across the top face of the pawl 6, and diamond shaped projection 8 fitting within the enlarged central opening 11 of the casing. A pair of oppositely disposed parallel leaf or plate springs 12 are mounted upon or within suitable slots 13 of the casing, one spring 80 upon each side of the opening 11, the diamond shaped projection 8 fitting between the two springs and engaging the inner faces 85 thereof. By fitting the diamond shaped projection between the springs as above described the same is normally forced into a 90 position wherein either two parallel faces of the projection lie flush against the springs 12, thus it will be seen that the pawl 95 is held in such a manner as to engage or entirely disengage the ratchet wheel 3.

The pawl when in a position as illustrated in Fig. 1 of the drawings is forced by the springs into engagement with the ratchet wheel, the turning of which in one direction is permitted without shifting the pawl, as 100 such turning of the wheel will not move the diamond shaped projection enough to cause a complete shifting of the pawl.

By sufficiently shifting the pawl and causing the other two parallel faces of the diamond shaped projection to lie flush against 105

the spring, the pawl is held entirely out of engagement with the ratchet wheel, and at the same time the entire casing is slightly swung upon its pivot, according to the length of the apertures 10 of the casing.

5 A casing cover 14 is fitted upon the top of the casing, the same being held in place through the medium of a plurality of nuts 15 carried by the vertically extending bolts 5.

10 It will be seen from the above taken in connection with the accompanying drawings that the pawl or dog may be swung into a position whereby it will either engage or disengage the ratchet wheel as desired; that by the provision of the diamond shaped projection a slight spring controlled movement of the pawl is permitted without entirely shifting the same; and that during the shifting of the pawl the entire casing is slightly moved according to the length of the apertures provided for the purpose of limiting such movement.

15 It is thought from the foregoing that the advantages and novel features of my invention will be readily comprehended.

20 I desire it to be understood that I may make slight changes in the construction and in the arrangement and combination of the several parts, provided such changes fall within the scope of the subjoined claims.

25 Having thus fully described my invention, what I claim as new and desire to secure by Letters Patent, is:—

1. A device as set forth including a ratchet wheel, a pivoted pawl having an angular projection symmetrically centered thereupon and integral therewith, and a pair of parallel resilient means in contact with said projection, to yieldably mount 30 said pawl in a number of positions.

2. A device as set forth including a ratchet wheel, a pivoted pawl having a diamond shaped projection symmetrically centered thereupon and integral therewith, and 35 a pair of parallel resilient means, each of which is in contact with a pair of adjacent faces of said projection, to yieldably mount said pawl in any of a number of positions.

3. A device as set forth including a ratchet wheel, a pivoted pawl having a projection formed with one set of adjacent angled faces, and an oppositely disposed set of oppositely parallel faces, and a pair of 45 resilient means, each in contact with one set of the said angled faces, to yieldably mount said pawl in any of a number of positions.

4. A device as set forth including a ratchet wheel, a pivoted pawl having an angular projection symmetrically centered thereupon and integral therewith, a pair of parallel resilient means in contact with said projection to yieldably mount said pawl in any of a number of positions, and means 60 mounting said resilient means for movement independent of said projection.

5. A device as set forth including a ratchet wheel, a pivoted pawl having a diamond shaped projection symmetrically centered thereupon and integral therewith, a pair of parallel resilient means, each of which is in contact with a pair of adjacent faces of said projection to yieldably mount said pawl in any of a number of positions, and means mounting said resilient means for movement independent of said projection. 75

6. A device as set forth including a ratchet wheel, a pivoted pawl having a projection formed with one set of adjacent angled faces, and an oppositely disposed set of oppositely parallel faces, a pair of resilient means, each in contact with one set of the said angled faces to yieldably mount said pawl in any of a number of positions, and means mounting said resilient means for movement independent of said projection. 80

7. A device as set forth including a ratchet wheel, a pivoted pawl having an angular projection symmetrically centered thereupon and integral therewith, a pair of parallel resilient means in contact with said projection to yieldably mount said pawl in any of a number of positions, a casing spacedly surrounding said projection for 90 mounting said resilient means, and means rendering said casing slidable to grant an independency of movement to said resilient means relative to said projection.

8. A device as set forth including a ratchet wheel, a pivoted pawl having a diamond shaped projection symmetrically centered thereupon and integral therewith, a pair of parallel resilient means, each of which is in contact with a pair of adjacent faces of said projection to yieldably mount said pawl in any of a number of positions, a casing spacedly surrounding said projection and mounting said resilient means, and means rendering said casing slidale to 100 grant an independency of movement to said resilient means relative to said projection. 105

9. A device as set forth including a ratchet wheel, a pivoted pawl having a projection formed with one set of adjacent angled faces, and an oppositely disposed set of oppositely parallel faces, a pair of resilient means, each in contact with one set of the said angled faces to yieldably mount said pawl in any of a number of positions, a casing spacedly surrounding said projection and mounting said resilient means, and means rendering said casing slidale to 115 grant an independency of movement to said resilient means relative to said projection. 120

10. A device as set forth including a ratchet wheel, a pivotally mounted pawl, an angular projection formed integrally with said pawl, a casing having an opening into which the said projection is fitted, springs 130

carried by said casing, one upon each side of said opening, the said springs adapted to engage the respective sides of said projection for controlling the movement of said pawl and for holding the same either into or out of engagement with the said ratchet, as and for the purpose set forth.

11. A device as set forth including a ratchet wheel, a pivoted pawl, a diamond shaped projection formed integrally with and upon the top face of said pawl, a loosely mounted casing, the said casing having an opening formed therein into which the said diamond shaped projection is fitted, a pair of oppositely disposed parallel leaf springs mounted upon the said casing and extending across the said opening, the said springs adapted to engage two of the parallel faces of the said projection for controlling the movement of the pawl and for holding the said pawl either into or out of engagement with the said ratchet, and means including a pair of vertically extending parallel bolts for limiting the movement of the said casing during the shifting of the pawl into and out of engagement with the said ratchet, as and for the purpose set forth.

12. A device as set forth including a ratchet wheel, a pivoted pawl having an angular projection symmetrically centered thereupon and integral therewith, a casing formed with an opening to spacedly surround said projection, a pair of parallel resilient means mounted in said casing to ex-

tend across said opening and to contact with said projection, and means rendering said casing slidable to grant an independency of movement to said resilient means with relation to said projection.

13. A device as set forth including a ratchet wheel, a pivoted pawl having a diamond shaped projection eccentrically centered thereupon and integral therewith, a casing formed with an opening to spacedly surround said projection, a pair of parallel resilient means mounted in said casing to extend across said opening and to each contact with a pair of adjacent faces of said projection, and means rendering said casing slidable to grant an independency of movement to said resilient means with relation to said projections.

14. A device as set forth including a ratchet wheel, a pivoted pawl, a projection formed on said pawl with one set of angled faces and an oppositely disposed set of oppositely parallel faces, a casing formed with an opening to spacedly surround said projection, a pair of parallel resilient means mounted in said casing to extend across said opening and to contact with a pair of adjacent faces of said projection, and means rendering said casing slidable to grant an independency of movement to said resilient means with relation to said projection.

ALBERT WILLSON.
